UNITED STATES PATENT OFFICE.

ZIGMINT GADOMSKI, OF JERSEY CITY, NEW JERSEY.

GARMENT-BAG.

1,363,726.

Specification of Letters Patent. Patented Dec. 28, 1920.

Application filed May 11, 1920. Serial No. 380,442.

To all whom it may concern:

Be it known that I, ZIGMINT GADOMSKI, citizen of Poland, and resident of Jersey City, in the county of Hudson and State of New Jersey, have invented certain new and useful Improvements in Garment-Bags, of which the following is a specification.

This invention relates generally to garment bags, and has for its main object the provision of such a bag which will successfully exclude the entry of moisture and dust, as well as moths, into the bags when the same are closed and contain clothing for storage.

The above and other objects will become apparent in the description below, in which characters of reference refer to like-named parts in the drawings.

Referring briefly to the drawings, Figure 1 is a front elevational view of my bag, partly in section.

Fig. 2 is an enlarged sectional view taken substantially on the line 2—2 of Fig. 1.

Fig. 3 is an enlarged sectional view taken substantially on the line 3—3 of Fig. 1.

Fig. 4 is an enlarged view of the clothes-hanging device contained within the bag.

Referring now in detail to the drawings, the numeral 1 represents the bag generally, composed of a pair of side members 2 and 3 joined around their closed edges by a closed flap 4. The edge of the bag indicated at 5 is the one through which the clothing may be inserted or withdrawn, and the only one which may be opened. The inner surface of the edge of each of the members 2 is at that portion lined with a strip of felt or the like 2^a, these strips being pressed together when the bag is closed and thus presenting a moisture and moth-proof closure.

Along the outer edge of each of the members 2 at the edge 5 are attached clasp hooks 6 about which a cord 7 is wound in order to close the bag. The whole bag may be suspended by a hook 8 at the top, the bag being

attached to the hook through the intermediate metal cap 9. On the underside of the top of the said bag below said cap 9, lies a metallic support 9^a having bayonet slots 13 therein as shown. A depending support 11^a extends from one end of the member 9^a, and a hooked-shaped member 10^a is pivotally attached thereto at 11. The hanger 10 is pivotally attached at one end to the member 10^a at 14, the hanger being formed as shown and having a hooked-end 12 adapted to engage the bayonet slot 13, in which the same, as is apparent, may be inserted so as to prevent its falling therefrom. Two such hangers are shown.

In use, the bag is first opened, the end 12 is disengaged from the slot 13 and drawn downward so that a suit or other article of clothing may be passed over the bent portion of the member 10 and onto the horizontal portion thereof, whence the end 12 is again inserted into the slot 13. Then the cord 7 is wound about the hooks 6 and the bag tightly closed for storage.

I claim:

In a garment bag, a hanger comprising a cap in the upper portion of said bag, a support depending from said cap, a bayonet slot in one end of said support having the open end of said slot substantially horizontal, a member rigidly attached to the other end of said support and depending therefrom, a hook-shaped member pivotally attached to said first member, a second hook-shaped member pivotally attached to said first hook-shaped member, the free end of said second hook-shaped member being curved into substantially the form of an S, said curved end being adapted to fit into said bayonet slot.

Signed at New York in the county of New York and State of New York this 5th day of May, A. D. 1920.

ZIGMINT GADOMSKI.
